UNITED STATES PATENT OFFICE.

CHARLES R. WOOD, OF EDMONTON, ALBERTA, CANADA.

POCKET CONSTRUCTION.

Application filed January 9, 1924. Serial No. 685,220.

To all whom it may concern:

Be it known that I, CHARLES R. Wood, a citizen of the United States, residing at Edmonton, in the Province of Alberta, and 5 Dominion of Canada, have invented certain new and useful Improvements in Pocket Constructions, of which the following is a specification, reference being had to the accompanying drawings.

10 This invention relates to an improved pocket construction and more particularly to an improvement in the construction of that pocket described in my prior patents, Reissue Patent No. 15,647, issued July 10, 15 1923, and Patent No. 1,477,925, issued December 18, 1923.

In these patents I have described a rule pocket which is relatively narrow and elongated and which is provided centrally at its 20 upper portion with a vertically extending pocket opening lying between the vertical edges of the pocket. The construction described in these prior patents is such that it is relatively expensive to manufacture, and 25 an important object of this invention is to provide a construction of this character whereby the pocket may be constructed of scraps or portions of material otherwise representing waste in cutting.

30 A further object of the invention is to provide a pocket construction of this character in which the general construction of the pocket is modified so as to enable the manufacturer to produce a pocket commensurate with the grade of overalls produced 35 so that he is enabled to provide overalls whether cheaply or expensively constructed with a pocket of this character.

40 A still further object of the invention is to provide a pocket of this character in which the labor incidental to construction is reduced and the cutting and stitching operations simplified.

45 These and other objects I attain by the construction shown in the accompanying drawings, wherein for the purpose of illustration is shown a preferred embodiment of my invention and wherein:—

50 Figure 1 is a characteristic front elevation of the pocket in all of its forms;

Figure 2 is a section on the line W—W of Figure 1;

Figure 3 is a section on the line X—X of Figure 1;

55 Figure 4 is a section on the line Y—Y of Figure 1;

Figure 5 is a section on the line Z—Z of Figure 1;

Figure 6 is a section on the line W—W of Figure 1, showing a modified construction of the section C of the pocket; 60

Figure 7 is a similar section showing a further modification of the construction of the section C;

Figure 8 is a section on the line Y—Y of 65 Figure 1 of the type of pocket embodying the modified section C;

Figure 9 is a section on the line Z—Z showing this modification;

Figure 10 is a section on the line Z—Z of 70 Figure 1, showing the modification of the section B of the pocket, in which modification an extra pocket is provided upon the outer surface of the main pocket;

Figure 10^a is a similar section showing 75 the same modification of the section B but with the upper thicknesses of the section B secured together so that no auxiliary pocket is formed;

Figures 11 and 12 are characteristic sections on the line X—X of Figure 1 with the modified section B, showing different manners of constructing this modified section; 80

Figure 13 is a section on the line Z—Z of 85 Figure 1, showing the construction in which both the sections B and C are modified by doubling the thickness thereof, the section B having one thickness separated at the top to provide the pocket opening;

Figure 14 is a similar section with the 90 plies of the section B secured together at their upper ends so that no pocket opening is formed;

Figure 15 is a section on the line X—X of 95 Figure 1, showing a further modification in which the section A is formed of two plies of material;

Figure 16 is a similar section showing the 100 sections A and B formed of two plies of material;

Figure 17 is a section on the line Y—Y of 105 Figure 1, showing the section A formed of two plies of material and the section C of a single ply;

Figure 18 is a similar section in which 110 both of the sections A and C are formed of two plies of material;

Figure 19 is a section showing a modified construction in which the section C is formed of two plies of material, one ply of which is secured to the lower ends of the sections A and B and the other ply of which

is free so as to form at the upper end of the section an opening affording access to the space between the plies;

Figure 20 is a characteristic front elevation where this form of construction of the section C is resorted to;

Figure 21 shows a modification in which the section C is doubled and the outer ply forms a hammer sling;

10 Figures 22 and 23 are modifications in which both the sections B and C are formed of two plies, the former showing the formation of two extra pockets and the latter the formation of one.

15 Referring now more particularly to the drawings, the pocket, as is evidenced by the characteristic elevations in Figures 1 and 20, is formed of three sections of material A, B and C. The sections A and B have 20 their adjacent edges overlapped and their remote edges secured to the body 10 of the associated fabric piece of the overalls or other garment to which they are applied by stitching 11. Across the tops of the sections a row of stitching 12 connects the 25 upper edges of the sections to the fabric piece 10 and, since these edges overlap for a portion of their length, connects the fabric pieces to one another at the upper end of the adjacent edges thereof.

30 The fabric piece C is secured along its upper edge by a row of stitching 13 to the lower edges of the sections A and B and, since the overlap above mentioned is provided, secures the adjacent edges of the sections A and B to one another along the lower end thereof. The fabric piece C is then stitched along its side edges to the fabric piece by stitching 14 and to the fabric piece along its bottom edge by stitching 15. By this method of construction a pocket is formed having an opening 16 affording access to the pocket which is arranged intermediate the side edges of the pocket at the 35 upper end of the pocket and which is substantially vertically extended, thus assuring against loss of articles from the pocket, since an article placed in the pocket and resting upon the lower end thereof will naturally incline to one side or the other of the pocket and hence will be out of line with the pocket opening 16 and unlikely to project and fall therefrom during bending movements of the leg.

40 It will be obvious that a pocket of this character can be formed from relatively small sections of material, enabling utilization of such small scraps of material as would be ordinarily wasted in cutting. Formed of these sections the pocket is, of course, capable of a considerable modification in the construction of each of the sections. In the sectional views shown in Figures 2, 3, 4 and 5 a pocket is illustrated in 45 which the sections A, B and C are each

formed of a single thickness of material. In Figures 6 and 7 I have shown the section C as formed of two thicknesses of material. In the form shown in Figure 6 the section C is formed of a single piece of material 70 folded back upon itself to provide the two thicknesses, while in Figure 7 this construction is further modified by the use of two separate pieces of material. By this construction the lower portion of the pocket 75 against which the tool rests when placed in the pocket is reinforced to prevent too rapid wear of the pocket.

80 In connection with this form of pocket attention is directed to Figures 19, 20 and 21. By an inspection of these figures it will be seen that the outer ply of material may be left free from the sections A and B along its upper edge to afford an opening 17 to the space between the plies of the section C, 85 thus enabling the use of the space between these plies for the reception of small articles which must be carried and forming upon the lower end of the completed pocket an outer auxiliary pocket. This construction 90 can be still further modified by leaving both the upper and lower edges of the outer ply of the section C free from attachment and securing the edges of both plies of the section. When so constructed the free outer 95 ply having the opening 17 at its upper end and an opening 18 at its lower end forms a hammer sling.

Attention is now more particularly directed to Figures 10 to 12 inclusive. In 100 these figures I have illustrated a form of pocket in which the sections A and C are formed of a single ply of material and the section B formed of two plies of material. As illustrated in Figures 11 and 12, these 105 two plies may be formed either by doubling a single piece of material or by employing two separate pieces of material. By a comparative inspection of Figures 10 and 10^a it will be seen that either only the inner ply 110 of the section B may be secured to the fabric piece 10 by the stitching 12 or both of the plies may be so secured. In the former construction the section B is provided at its upper end with an opening 19 affording 115 access to the space between the sections so that the section B provides upon the outer surface of the pocket an auxiliary pocket for the reception of pencils and the like. In the latter construction, where the upper 120 edges of the section are secured together, if desired, a buttonhole opening or openings 20 may be provided permitting the insertion of articles to the space between the sections. In these forms of construction a section on the line Y-Y of Figure 1 will be similar 125 to that section shown in Figure 4.

130 In Figures 13 and 14 a section on the line Z-Z of Figure 1 is shown through a modified construction in which both the sections

B and C are doubled and the section A is formed of a single piece of material. In this form of construction either of the sections B and C can have the outer ply thereof left separated at the upper end to form upon the outer surface of the main pocket a second pocket, as illustrated in Figures 13 and 23 respectively, or both of the sections can have the outer ply so separated, as illustrated in Figure 22, in which event two separate pockets are formed upon the outer surface of the main pocket. In this form of construction the characteristic sections shown on the line X—X in Figures 11 or 12 will apply and the characteristic sections on the line W—W shown in Figures 6 and 7 will apply. In the forms shown in Figures 15 and 17 the section A is doubled in thickness and the sections B and C are formed of a single ply of material. As indicated by the dotted lines in Figure 17, the outer ply of the section A may be left separated to provide a pocket opening 21 affording access to the space between the plies or both plies may be included in the stitching 12. With this form of construction the characteristic section on the line Z—Z of Figure 1 will apply and the characteristic section shown in Figure 2 and 30 taken on the line W—W of Figure 1 will apply.

In Figure 16 I have illustrated a form in which the modification of the sections is extended to the section B, the sections A and 35 B being doubled and the section C being single. In this form of construction the characteristic section upon the line Z—Z of Figure 1, as represented in Figures 10 or 10^a, will apply and the characteristic 40 section on the line Y—Y, as shown in Figure 17, will apply.

In Figure 18 the modification is extended to all three of the sections, each of the three sections being doubled. As shown in this figure, the outer ply of the section A may be left separated if so desired as may the outer 45 ply of the section C. A section on the line X—X of Figure 1 in this form of construction will appear as in Figure 16, while a section on the line Y—Y will appear as in Figures 14 or 23. A section on the line W—W would appear as in either of Figures 6 or 7.

It will be obvious from the foregoing that 55 I have provided a pocket which by extremely simple changes in the form of construction thereof is capable of a wide range of modification, for each of these modifications embody the principle and valuable features of the parent construction and each having some particular feature to recommend it. Where any of the sections is doubled, if desired, an extra pocket may be produced and this doubling of the material will, of course, 60 give added strength to the pocket at the

point where strain is placed thereon. Where the two plies of the section C are secured together at their lower edge the greater strain of the weight of a tool applied to this section will be placed and it is accordingly substantially immaterial whether the upper edges of the plies are secured together or not. The strain placed upon the outer ply will be supported by the stitching of the sections at each place. The same holds true of the sections B and C. The strain placed upon these sections will be by the weight applied against the outer or attached edges of the sections by a tool resting upon the lower end of the pocket and inclining to one side or the other. This strain will be materially increased during bending movements of the legs of the wearer of the garment to which the pocket is applied, at which times the rigid tool resting upon the bottom of the pocket will be forcibly engaged with the side edges of the upper end of the pocket structure. The doubling in thickness reinforces these edges regardless of whether the upper edge of the sections A or B is attached through both plies or through but a single 55 ply. The construction where a single thickness is employed for either of the sections is necessarily quite cheap and it will be obvious that by forming these sections of a single ply very small pieces of fabric can be employed in the construction of the pocket thus lessening waste. This holds true to a greater or lesser extent where one or two sections are doubled in thickness and a single 60 section or two sections are formed from a single thickness of material. I accordingly do not limit myself to the specific structure of any particular form of the pocket except as hereinafter claimed.

I claim:

1. A pocket consisting of an outer wall formed of three sections and an inner wall formed of a single piece of material, two of said sections of the outer wall forming the upper half of the outer wall, the third section forming the lower half thereof, the said two sections having their adjacent side edges overlapped, stitching securing the remote side edges of the two sections to the fabric piece forming the inner wall, other stitching securing the upper edges of the sections to the fabric piece, the last named stitches securing the adjacent overlapped edges of the two sections together at the upper ends thereof, the upper edge of the third section being stitched to the lower edges of the said two sections, said stitching securing together the overlapped adjacent edges of the two sections at the lower ends thereof, the side and bottom edges of said third section being stitched to the fabric piece forming the rear wall.

2. A pocket consisting of an outer wall formed of three sections and an inner wall

formed of a single piece of material, two of said sections of the outer wall forming the upper half of the outer wall, the third section forming the lower half thereof, the said two sections having their adjacent side edges overlapped, stitching securing the remote side edges of the two sections to the fabric piece forming the inner wall, other stitching securing the upper edges of the sections to the fabric piece, the last named stitches securing the adjacent overlapped edges of the two sections together at the upper ends thereof, the upper edge of the third section being stitched to the lower edges of the said two sections, said stitching securing together the overlapped adjacent edges of the two sections at the lower ends thereof, the side and bottom edges of said third section being stitched to the fabric piece forming the rear wall, the third section being formed of two plies of material.

3. A pocket consisting of an outer wall formed of three sections and an inner wall formed of a single piece of material, two of said sections of the outer wall forming the upper half of the outer wall, the third section forming the lower half thereof, the said two sections having their adjacent side edges overlapped, stitching securing the remote side edges of the two sections to the fabric piece forming the inner wall, other stitching securing the upper edges of the sections to the fabric piece, the last named stitches securing the adjacent overlapped edges of the two sections together at the upper ends thereof, the upper edge of the third section being stitched to the lower edges of the said two sections, said stitching securing together the overlapped adjacent edges of the two sections at the lower ends thereof, the side and bottom edges of said third section being stitched to the fabric piece forming the rear wall, the third section being formed of two plies of material, the stitching connecting the said two sections and the third section extending through the inner ply only of the third section.

4. A pocket consisting of an outer wall formed of three sections and an inner wall formed of a single piece of material, two of said sections of the outer wall forming the upper half of the outer wall, the third section forming the lower half thereof, the 55 said two sections having their adjacent side edges overlapped, stitching securing the remote side edges of the two sections to the fabric piece forming the inner wall, other stitching securing the upper edges of the 60 sections to the fabric piece, the last named stitches securing the adjacent overlapped edges of the two sections together at the upper ends thereof, the upper edge of the third section being stitched to the lower edges of the said two sections, said stitch-

ing securing together the overlapped adjacent edges of the two sections at the lower ends thereof, the side and bottom edges of said third section being stitched to the fabric piece forming the rear wall, the third section being formed of two plies of material, the stitching connecting the said two sections and the third section extending through the inner ply only of the third section, the stitching connecting the lower edge of the third section to the fabric piece forming the inner wall of the pocket extending through the inner ply only of the section. 70 75

5. A pocket consisting of an outer wall formed of three sections and an inner wall 80 formed of a single piece of material, two of said sections of the outer wall forming the upper half of the outer wall, the third section forming the lower half thereof, the said two sections having their adjacent side 85 edges overlapped, stitching securing the remote side edges of the two sections to the fabric piece forming the inner wall, other stitching securing the upper edges of the sections to the fabric piece, the last named 90 stitches securing the adjacent overlapped edges of the two sections together at the upper ends thereof, the upper edge of the third section being stitched to the lower edges of the said two sections, said stitching 95 securing together the overlapped adjacent edges of the two sections at the lower ends thereof, the side and bottom edges of said third section being stitched to the fabric piece forming the rear wall, one of said 100 sections of the outer wall being formed with outer and inner plies and having an opening affording access to the space between the plies.

6. A pocket consisting of an outer wall 105 formed of three sections and an inner wall formed of a single piece of material, two of said sections of the outer wall forming the upper half of the outer wall, the third section forming the lower half thereof, the 110 said two sections having their adjacent side edges overlapped, stitching securing the remote side edges of the two sections to the fabric piece forming the inner wall, other stitching securing the upper edges of the 115 sections to the fabric piece, the last named stitches securing the adjacent overlapped edges of the two sections together at the upper ends thereof, the upper edge of the third section being stitched to the lower 120 edges of the said two sections, said stitching securing together the overlapped adjacent edges of the two sections at the lower ends thereof, the side and bottom edges of said third section being stitched to the fabric 125 piece forming the rear wall, one of said sections of the outer wall being formed with outer and inner plies, the stitching at the upper edge of said section extending through the inner ply only thereby pro- 130

viding an opening for access to the space between the plies.

7. A pocket consisting of an outer wall formed of three sections and an inner wall formed of a single piece of material, two of said sections of the outer wall forming the upper half of the outer wall, the third section forming the lower half thereof, the said two sections having their adjacent side edges overlapped, stitching securing the remote side edges of the two sections to the fabric piece forming the inner wall, other stitching securing the upper edges of the sections to the fabric piece, the last named stitches securing the adjacent overlapped edges of the two sections together at the upper ends thereof, the upper edge of the third section being stitched to the lower edges of the said two sections, said stitching securing together the overlapped adjacent edges of the two sections at the lower ends thereof, the side and bottom edges of said third section being stitched to the fabric piece forming the rear wall, certain of said sections being formed with outer and inner plies and each having an opening affording access to the space between the plies.

8. A pocket consisting of an outer wall formed of three sections and an inner wall formed of a single piece of material, two of said sections of the outer wall forming the upper half of the outer wall, the third section forming the lower half thereof, the said two sections having their adjacent side edges overlapped, stitching securing the remote side edges of the two sections to the fabric piece forming the inner wall, other stitching securing the upper edges of the sections to the fabric piece, the last named stitches securing the adjacent overlapped edges of the two sections together at the upper ends thereof, the upper edge of the third section being stitched to the lower edges of the said two sections, said stitching securing together the overlapped adjacent edges of the two sections at the lower ends thereof, the side and bottom edges of said third section being stitched to the fabric piece forming the rear wall, all of said sections being formed with outer and inner plies, the stitching at the upper edges of said sections extending through the inner ply only, the inner ply only of the lower edge of the third section being included in the stitching of such edge.

9. A pocket consisting of an outer wall formed of three sections and an inner wall formed of a single piece of material, two of said sections of the outer wall forming the upper half of the outer wall, the third section forming the lower half thereof, the said two sections having their adjacent side edges overlapped, stitching securing the remote side edges of the two sections to the fabric piece forming the inner wall, other stitching securing the upper edges of the sections to the fabric piece, the last named stitches securing the adjacent overlapped edges of the two sections together at the upper ends thereof, the upper edge of the third section being stitched to the lower edges of the said two sections, said stitching securing together the overlapped adjacent edges of the two sections at the lower ends thereof, the side and bottom edges of said third section being stitched to the fabric piece forming the rear wall, said third section being formed with outer and inner plies, the inner ply being secured at its upper edge to the lower edges of the said two sections and at its side and edges to the fabric piece forming the inner wall, the outer ply being secured to the fabric piece only at its side edges.

In testimony whereof I hereunto affix my signature.

CHARLES R. WOOD.
